(57) **CLAIM**

The ornamental design for a pinch guard as shown and described.

DESCRIPTION

FIG. 1 is a first isometric view of a pinch guard;
FIG. 2 is a second isometric view of the pinch guard;
FIG. 3 is a third isometric view of the pinch guard;
FIG. 4 is a fourth isometric view of the pinch guard;
FIG. 5 is a front elevational view of the pinch guard;
FIG. 6 is a rear elevational view of the pinch guard;
FIG. 7 is a right side view of the pinch guard;
FIG. 8 is a left side view of the pinch guard;
FIG. 9 is a top plan view of the pinch guard; and,
FIG. 10 is a bottom plan view of the pinch guard.
The broken lines in the Figures show portions of a pinch guard that form no part of the claimed design.
